UNITED STATES PATENT OFFICE.

EDWARD P. CRESSLER, OF NEWTON, KANSAS.

STEREOSCOPIC FILM OR PLATE PACK.

Application filed February 12, 1926. Serial No. 87,876.

This invention relates to packages of sensitized films or plates for use individually in dental X-ray work.

The primary object of the invention is the provision of a double film pack whereby, in stereoscopic work, for instance, two views may be taken with the same pack by merely inverting the pack in its holder, and the two views may be retained together until they are to be developed.

Another object of the invention is to provide a double film pack including two single packs separated and partially encased by metal or other material impervious to Roentgen rays whereby the film in one of the packs will be unaffected by the rays during the exposure of the film in the other pack.

Another object of the invention is to provide a film pack for individual use which will be simple to manufacture, which will be sufficiently waterproof for all practical purposes, and which is sufficiently flexible to permit bending thereof as needed.

Another object of the invention is to provide a pack of this character embodying means whereby the pack may be quickly and easily opened and the film or films removed therefrom.

A further object of the invention is to provide a pack-opening device normally disposed partially within the pack and having pivotal connection with the film or films whereby it serves also as a means for withdrawing the films from the pack and for holding them during developing operations.

With these and other objects in view, as will become apparent as the description proceeds, the invention consists of the novel features of construction, combinations of elements, and arrangements of parts hereinafter to be fully described and pointed out in the claims.

A full and complete understanding of the invention may be obtained from a consideration of the following detailed description, taken in connection with the accompanying drawings forming a part of the disclosure, it being understood that while the drawings show certain practical embodiments of the invention, the latter is not to be confined to the showing thereof but may be changed or modified so long as such changes and modifications mark no material departure from the salient features of the invention as hereinafter described and claimed.

55 In these drawings:

Figure 1 is a view in top plan of a film

pack embodying certain features of my inventive-concept;

Fig. 2 is a view in side elevation thereof;

Fig. 3 is a fragmentary view in plan 60 thereof illustrating the pack-opening and film-handling element in extended position;

Fig. 4 is a longitudinal sectional view through the pack, taken on line 4-4 of Fig. 1;

Fig. 5 is an enlarged fragmentary view illustrating the manner in which the opening strip is attached to the film;

Fig. 6 is a fragmentary view in plan of a 70 modified form of pack-opening device;

Fig. 7 is a similar view of another modified form of opening device;

Fig. 8 is a view in longitudinal section of a double film pack for stereoscopic work;

Figs. 9 and 10 are fragmentary sectional 75 views illustrating other forms thereof; and

Fig. 11 is a perspective view of the double film pack illustrated in Fig. 10, one of the film packs being removed therefrom and the pack opened by means of the opening and 80 handling device.

Referring to the drawings, the reference-character 1 designates, generally, a film holder for stereoscopic X-ray work comprising, in this instance, a double container 2 formed up of lead or the like material to provide a central plate or partition 3 having integral flanges 4 and 5 extending substantially at right angles from the periphery of the opposite faces of the partition to constitute cup-like chambers 6 to receive a pair of single film packs 7.

The flanges 4 and 5, as shown in Fig. 8, are both curved and meet to define a groove 8 therebetween which adapts it particularly 95 well for use in a holder as shown and described in applicant's co-pending application Serial No. 87,390, filed February 10, 1926. As shown in Fig. 9, the flanges 4 and 5 are curved so that together they form an outwardly convex side wall 9 of the film holder. In Fig. 10, the flanges 4 and 5 are shown straight except for the free edges thereof which are inturned as at 10 to overlie the film 100 packs 7 disposed therein.

Each film pack 7 preferably contains the following elements: A sheet 11 of protective paper, opaque to ordinary light but pervious to Roentgen rays, one or more (one only being shown) sheets 12 of sensitized film, and 110 a sheet 13 of metallic foil, such as lead, all of these sheets being of the same size.

Around the enclosed leaves enumerated above is placed a wrapping sheet 14, of opaque paper, of greater area than the enclosed sheets. This overlies the sheet 11 and its edges are bent up around the edges of the contained sheets at 15 and bent to overlie the surface of sheet 13 in a continuous flange or fold 16 extending around the entire periphery of the package. A sheet 17 of paper or other suitable material, coated with an adhesive, is attached by the adhesive around all but one corner 18 of its entire edge to this fold 16, overlapping this to an extent sufficient to insure a firm and reliable adherence. 15 Preferably and as shown, each film 12 within the pack 7 is provided with means whereby it may be withdrawn from the pack, which means also serves as a pack-ripping or opening element. This means, as shown in Figs. 1 to 5, inclusive, and 11 comprises a thin flexible metallic strip 19, preferably pervious to Roentgen rays and longer than the film, pivotally attached to the film adjacent one corner thereof by means of a struck up 20 lug 20 passing through an aperture 21 in the film and bent down into parallelism therewith. In order to identify the films, for instance to determine which of the films from a pack as shown in Fig. 8 should be positioned to the left and which to the right for stereoscopic observation, suitable characters or marks 22 designating rights and lefts are provided on the opening strips either by application of paint containing any metallic 25 substance impervious to X rays or a suitable piece of metal impervious to X rays thereto. The strips 19, on the other hand, may themselves be of base metal and have suitable characters or marks stenciled therein. The 30 single packs 7 will, of course, require an exterior marking corresponding to that on the film or films contained therein.

In forming the single pack 7, the free end 23 of the strip 19 punctures and extends 45 through the wrapper 14 and has secured fast thereto a gripping piece 24, which is impervious to ordinary light, but preferably pervious to X rays, and envelops the corner of the pack, thus preventing light from passing 50 through the perforation made by the strip 19. This corner piece may or may not be adhesively secured to the pack.

In lieu of the opening means just described, a corner piece 25 may be adhesively secured to the corner of the pack and will 55 serve as a means for opening the corner, after which the pack may be fully opened with ease. In the event that the corner piece 25 is constructed of a material impervious to 60 X ray, the side adjacent sheet 11 may be cut out as at 26 so as not to interfere with the passage of the rays to the film.

If desired, in lieu of the corner piece 25, an opening element 27, constructed of any desired material preferably pervious to X rays, 65

may be adhesively secured over an entire edge portion of the pack 7, as shown in Fig. 7. In this form, any desired identifying mark may be produced on the film by securing a marker 28 of material impervious to X ray 70 upon the corner piece 25.

It will be observed that each of the pack-opening devices above described includes a portion projecting somewhat from the pack which may be readily detected in the dark 75 room and permits quick location of the opening means.

What I claim is:

1. A film pack comprising a plate, flanges extending angularly from the periphery of 80 both surfaces thereof to produce therewith a pair of cup-like chambers, and an enclosed sensitized film disposed in each chamber.

2. A film pack comprising a plate, integral flanges extending at right angles from the 85 periphery of both surfaces thereof to produce therewith a pair of cup-like chambers, and an enclosed sensitized film disposed in each chamber.

3. A film pack comprising a plate composed of a substance impervious to Roentgen rays, integral flanges extending at right angles from the periphery of both surfaces thereof to produce therewith a pair of cup-like chambers, and an enclosed sensitized film 95 disposed in each chamber.

4. A film pack comprising a plate, integral flanges extending at right angles from the periphery of both surfaces thereof to produce therewith a pair of cup-like chambers, and an enclosed sensitized film disposed in each chamber, the free edge of the flanges being 100 inturned and engaging the means enclosing the respective films.

5. A film pack comprising a plate composed of a substance impervious to Roentgen rays, integral flanges extending at right angles from the periphery of both surfaces thereof to produce therewith a pair of cup-like chambers, and an enclosed sensitized film 110 disposed in each chamber, the free edge of the flanges being inturned and engaging the means enclosing the respective films.

6. A film pack for stereoscopic X-ray work, including a plurality of enclosed sensitized 115 films and means separate from the films for maintaining the films fixed in such relative positions that one of the films will be unaffected by X rays during the exposure of the other film.

7. A film pack including a sensitized film, an enveloping wrapper, and a pack-opening element disposed partially within the pack and having pivotal connection with the film.

8. A film pack including a sensitized film, 125 an enveloping wrapper, a pack-opening element having pivotal connection with the film and extending through the wrapper, and a gripping element fast to the opening element and pack.

9. A film pack including an enveloping wrapper, a sensitized film disposed therein, and means having connection with the film for opening the pack for withdrawing the film therefrom. 10. A film pack including a sensitized film having an aperture adjacent a corner thereof, an enveloping wrapper therefor, and a pack-opening and film-holding element disposed partially within the pack and having a struck up lug extending through said aperture. 11. A film pack including a sensitized film, an enveloping wrapper therefor, and means connected to the film for opening the pack and for handling the film during film-developing operations. 12. A film pack including a sensitized film, an enclosing wrapper therefor, and a pack-opening and film-withdrawing means pivotally connected to the film and projecting through the wrapper. 13. A film pack including a sensitized film, an enclosing wrapper therefor, and a pack-opening and film-withdrawing means pivotally connected to the film and projecting through the wrapper. 14. A film pack including a sensitized film, an enclosing wrapper therefor, a pack-opening and film-withdrawing means pivotally connected to the film and projecting through the wrapper, and a sealing and gripping element fast to the wrapper and to the projecting portion of said pack-opening and film-withdrawing means.

In testimony whereof, I have affixed my signature hereto.

EDWARD P. CRESSLER.
